UNITED STATES PATENT OFFICE.

GILBERT W. GOODRIDGE, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ATTACHMENT-PLUG.

1,340,856.

Specification of Letters Patent. Patented May 18, 1920.

Application filed December 31, 1917. Serial No. 209,681.

To all whom it may concern:

Be it known that I, GILBERT W. GOODRIDGE, a citizen of the United States of America, and residing in Bridgeport, in the 5 county of Fairfield and State of Connecticut, have invented certain new and useful Improvements in Attachment-Plugs, of which the following is a specification.

My invention relates to attachment plugs, 10 and the object of my invention is to provide a simple and rugged electrical device of this character which is not only economical to manufacture, but also easy to wire and efficient in service.

15 Referring to the accompanying drawings, Figure 1 is a plan view of an attachment plug in which my invention is embodied in one form;

Fig. 2 is a vertical section therethrough 20 on the line 2—2, Fig. 1;

Fig. 3 is a cross section on the line 3—3, Fig. 2;

Fig. 4 is an inverted plan of the cap member of the plug;

25 Fig. 5 is a vertical section on the line 5—5, Fig. 1; and

Fig. 6 is a perspective of one of the securing screws for attaching the cap to the body of the plug.

30 In the form here shown, the plug comprises a body member 10 and a cap member 11, both of insulating material and preferably of molded insulation. The cap member is recessed on its inner face at 12 to afford 35 a chamber of generally oval form to accommodate the strain relief knot 13 tied in the ends of the two wires which are combined in the insulating casing of the wire cable 14. This cable is generally oval in transverse 40 section and enters the chamber 12 through a passage 15 of similar shape, the longer axis of which substantially corresponds to the longer axis of the chamber 12. A marginal flange 16 on the inner face of the cap fits 45 over the cap end of the body 10 of the plug and forms a snug joint therewith. In order properly to position the cap upon the body, especially with relation to the oval recess 12 and the binding terminals hereinafter to be

50 described, a lug 17 is provided which projects radially inward from the flange 16 and takes into a corresponding marginal recess 18 in the cap end of the plug body 10. Securing screws 19 and 20 pass through the 55 cap 11 on opposite sides of the chamber 12

at the point of its shorter diameter, and take into short tapped bushings 21 and 22 molded into the upper portion of the plug body 10. In order to prevent accidental loss of the screws 19 and 20 when the cap is detached, I provide them with thin washers 23 screwed thereon to a point beyond the threaded ends of the screws and accommodated in recesses 24 and 25 in the inner face of the cap 11. When the screws are freed 65 from the bushings 21 and 22, the washers 23 still engage the threads of the screws and prevent the latter from falling out of the holes 26 and 27 through which they pass. In order to prevent the bushings from turning 70 with the screws 19 and 20 when the latter are set down hard, the bushings may be of non-circular shape, or their heads may be provided with serrations, as at 28.

The body 10 of the plug is longitudinally 75 perforated at 29 and 30 to receive the binding screws 31 and 32 by which connection is established between the cable wires and the plug terminals 33 and 34. The sleeves 35 and 36 of the terminals are internally tapped 80 to receive the threaded ends of the screws 31 and 32 and are similarly provided with a milled flange 37 adjacent the projecting ends of the terminals to hold the same against rotation when the binding screws 31 and 32 85 are set up. In the cap end of the body member 10, shallow wells 38 and 39 are provided to form seats for the heads 40 and 41 of the binding screws 31 and 32, but are extended to one side of the latter to accommodate the 90 ends of the connecting wires. The extensions of the wells 38 and 39 project in opposite directions with relation to the axial plane of the binding screws, thus insuring the separation of the bared ends of the connecting wires and preventing any danger of 95 short circuit. It will be noted, furthermore, that the heads 40 and 41 of the binding screws are of substantially the same diameter as the wells 38 and 39, and thus coöperate 100 with the side walls of the latter to house in the wire beards and confine the same within the margins of the respective wells 38 and 39.

Passing transversely through the body between the terminals and at the entering end 105 of the plug, is a securing pin 42, the projecting ends of which engage the bayonet slot fastening of the usual "Edi-Swan" socket or receptacle and hold the plug ter- 110

minals 33 and 34 in engagement with the corresponding terminals of the receptacle.

It will be recognized that the plug is of extremely simple and economical construction and at the same time presents a very rugged and serviceable fitting adapted to withstand rough handling in use without injury. Various modifications in details of construction will readily occur to those skilled in the art which do not depart from what I claim as my invention.

I claim as my invention:

1. An attachment plug having cap and body members and screw means for uniting the same, wiring wells formed in the cap end of the body member, plug contacts fixed to the body member and exposed at the entering end thereof, binding screws having heads seated in said wells, and threaded shanks taking into said contacts to establish electrical connection between the wires clamped beneath the heads of the screws in the wiring wells and the plug contacts.
2. An attachment plug having cap and body members and means for uniting the same, wire terminals on opposite sides of the axis of the body member at the cap end thereof, a strain relief knot chamber in the cap member and means piercing the cap on opposite sides of its axis at the point of short diameter of said chamber for securing the cap to the body with the long axis of the chamber substantially alined with the plane of the wire terminals on the body member.
3. An attachment plug having independent cap and body members, said body having at its entering end plug contacts and associated tapped bushings integral therewith molded into the body, binding screws taking into said tapped bushings, the heads of said binding screws being accommodated in recesses formed in the cap end of the body, insulating means projecting from the sides of the body member by which the plug may be connected to a coöperating receptacle, insulating bushings molded into the cap end

of the body member and screws piercing the cap member and taking into said bushings to hold the parts assembled.

4. An attachment plug comprising independent cap and body members, the body member having contacts at its entering end, binding screws extending parallel to the axis of the plug and taking into said contacts to establish electrical connections therewith, tapped bushings molded into the body piece on a plane substantially at right angles to the plane of the plug contacts, in combination with the screws passing through said cap and taking into said tapped bushings to unite said cap and body members.

5. An attachment plug comprising independent cap and body members, the body member having contacts at its entering end, binding screws extending parallel to the axis of the plug and taking into said contacts to establish electrical connections therewith, tapped bushings molded into the body piece on a plane substantially at right angles to the plane of the plug contacts, in combination with the screws passing through said cap and taking into said tapped bushings to unite said cap and body members, together with stud means projecting from the sides of the body member substantially in the plane of the tapped bushings and serving as means by which the plug may be connected to a coöperating receptacle.

6. In an attachment plug, a body of insulating material having at its entering end a pair of contacts, binding screws extending in a direction substantially parallel to the axis of the plug and taking into the contact from the cap end of the plug, together with a pin passing transversely through the body of the plug between the contact and projecting from the opposite sides of the body to form studs, by which the plug may be connected to a coöperating receptacle.

In testimony whereof I have signed my name to this specification.

GILBERT W. GOODRIDGE.
